UNITED STATES PATENT OFFICE.

CLEMMA R. RANEY, OF CHICAGO, ILLINOIS, ASSIGNOR TO INTERNATIONAL HARVESTER COMPANY, OF CHICAGO, ILLINOIS, A CORPORATION OF NEW JERSEY.

SHOCKER.

Application filed June 18, 1923. Serial No. 645,991.

This invention relates to grain shockers and more particularly to an improved construction in which the butts of the shocks set up by the shocker are adequately spread to insure the proper ventilation and airing for the purpose of curing or drying out the grain in the shock.

The principal object of the present invention is to provide an improved shocking machine which will build stable shocks in the field capable of standing up under all weather conditions and in which the butts of the sheaves are uniformly spaced to admit air to the shock.

15 A further object is to provide an improved means for automatically spreading the butt or base of the shock in longitudinal and transverse directions.

I obtain these objects by providing improved means which cooperate with the shock discharging mechanism and engage the butts of all the sheaves, spreading these sheaves transversely as the shock is being set, and longitudinally as the shocker is withdrawn 25 from the shock so that these butts are adequately spread in both directions forming a substantial base and thereby permitting sufficient ventilating space between all the sheaves of the shock.

30 In order to disclose my invention, I have illustrated one embodiment of the same as shown in the accompanying drawings. It is, of course, to be understood that the embodiment shown herein for the purposes of 35 illustration may be modified without departing from the spirit of my invention.

Referring to the drawings:

Fig. 1 is a top plan view of the shocker having my improvement embodied therein;

40 Fig. 2 is a side elevational view of Fig. 1;

Fig. 3 is a rear elevational view of Fig. 1; and

45 Fig. 4 is an enlarged detail view showing the latch and pawl mechanism for locking the butt spreading mechanism in their normal or vertical position.

The shocker shown is of the general type described and claimed in my U. S. Letters Patent No. 1,231,195, June 26, 1917, and 50 No. 1,293,922, February 11, 1919, a rearwardly swinging sheaf delivery member or fork 12 being used, which is carried on a shocker frame 13 and movable by means of a resilient pitman connection 14 about 55 an axis on a shaft 15 from its sheaf re-

ceiving position, as shown in the full lines in Fig. 1, wherein it rests beneath the deck of the binder (not shown) to its sheaf delivering position, (shown in dotted lines in Fig. 1) wherein it delivers sheaves in prostrate position in an upwardly and rearwardly movable shock receptacle 16 carried by the rear end of the shocker frame.

Also, after the manner of construction described in my U. S. Letters Patent No. 1,231,195, June 26, 1917, and No. 1,242,112, October 2, 1917, when enough sheaves have been delivered to the shock receptacle 16 to build a shock therein of a predetermined size, a needle 17 and knotting mechanism 18 are 70 thrown into operation to compress and bind the shock and at the completion of the compressing and binding operation, through the rotation of the knotter shaft 19, the shock receptacle 16 is moved upwardly and rearwardly to deposit the shock in an upright position on the ground.

The fork 12 and all the other operative mechanisms upon the present shocker are driven from a longitudinally disposed power 80 shaft 20 which is of extensible and flexible character deriving its power from the crank shaft of the harvester (not shown). As shown, the rear end of the shaft 20 is journaled in a bracket 21 on the shocker frame. 85

As described in my Patent No. 1,231,195, June 26, 1917, and in a manner common to all shockers of this type, a continuously operating clutch member 22 is secured to the shaft 20. Engageable with the continuously 90 operating clutch member 22, and adapted to be driven thereby, is an intermittently operating clutch member 23 which is normally controlled by a pawl (not shown). Formed integrally with the intermittently operating 95 clutch member 23 is a sprocket 24. The sprocket 24 operatively drives the knotter shaft 19 by means of a chain 25. The chain 25 is trained about the sprocket 24 and about a sprocket 26 keyed to the shaft 19. Secured to the rear end of the knotter shaft 19 is a crank 27. The free end of the crank 27 is provided with a stud 28 which has pivotally secured thereto a knuckle joint and pitman connection 29. The lower end of the pitman connection 29 is pivotally secured at 30 to a crank 31. The crank 31 is pivotally mounted on the grainward end of the crank shaft 32. Secured to the grainward 100 end of the crank shaft 32 adjacent crank 31 105

110

is a second crank 33. The crank 33 is adapted to be engaged by a gravity pawl 34 in the manner hereinafter described. The stubbleward end of the crank shaft 32 is provided with a forwardly extending arm 35. The free end of the arm 35 is provided with a roller 36 which is adapted to engage the bottom side of the shock receptacle 16 as the same is actuated about its pivot in the normal operation of setting a shock. Secured to the opposite sides of the main frame member 13 are brackets 37. Secured in the brackets 37 is a transversely extending pipe 38. Tiltably mounted by means of hinge brackets 16 on the pipe 38 in a manner to be swung upwardly and rearwardly with respect thereto is the shock receptacle 16.

My improved mechanism for spreading the sheaves in the shocks set by the shock receptacle during the setting of the shock and also during the withdrawal of the shocker from the shock will next be described. Secured to the pipe 38 by means of bolts 39 are bearing brackets 40. Pivotally mounted in the bearing brackets 40 is a transversely extending butt tooth pipe 41. The pipe 41 is prevented from lateral displacement by cotter pins 42. Secured intermediate the ends of the pipe 41 are two vertically extending tines 43. Positioned on the opposite side of the vertically extending tines 43 are two pairs of pivoted tines 44. The lower ends of the tines 44 are secured to U-shaped brackets 45 which are adapted to embrace the pipe 41 and are pivoted thereto by means of a pin 46. The pivotal action of the tines 44 is controlled by cam members 47 which are arranged concentrically with respect to the pipe 41 and are secured to the pipe 38 by means of bolts 48. From the above description, it will be understood that as the shaft or pipe 41 together with the tines 44 is rotated from the vertical position or full line position shown in Fig. 2 to the dotted line position shown in this figure, these tines will be swung outwardly to the dotted line position shown in Fig. 1 by reason of the tines engaging the slotted or camming surfaces 49 in the cam members 47. The tines together with the shaft 41 are normally returned to their vertical position or the position shown in full lines in Fig. 2 by means of an extension spring 50 having one end secured to the main frame 13 and the other end secured to the pipe 41 at 51.

In connection with my new butt spreading mechanism, I have provided means for automatically locking and unlocking the tines to the shock receptacle which comprises a latch member 52 pivoted at 53 to a bracket 54 secured to the receptacle 16. Formed integrally with the bracket 54 is a vertically extending ear 55. Pivotal secured to the ear 55 is a rod 56. Embracing the rod 56 is a compression spring 57 which normally en-

gages or forces an ear 58, which is formed integrally with the latch 52, rearwardly and this presses the latch 52 into engagement with a pawl 59 secured to the pipe 41 by means of bolts 60. The pawl 59 is provided with a forwardly extending portion 61 which is adapted to engage the underside of the latch and thereby release the latch 52 from the pawl 59 when the receptacle 16 is discharging a shock as shown in Fig. 4. In other words, as the shock receptacle is swung upwardly and rearwardly about its pivot on the pipe 38, the butt spreading mechanism including the pipe 41 and pawl 59 is also swung rearwardly until the positions shown in Fig. 4 are reached in which the portion 61 of the pawl 59 engages the underside of the latch 52 and thereby unlocks the pawl, releasing the butt teeth or tines 43 and 44 and thereby permitting them to swing downwardly free from the shock receptacle 16.

A detailed description of all of the mechanism shown in these drawings has not been made because it is believed that the construction here shown is sufficiently described and claimed in the U. S. Letters Patent above mentioned.

In the operation of my improved shock spreading mechanism, it will of course be understood that the shock is built prostrate in the receptacle 16 by means of the sheaf delivery member 12, delivering or conveying the sheaves from the binder deck of the harvester to the sheaf receptacle. When the sheaves in the shock receptacle have reached a predetermined height, the intermittently operated clutch member 23 is tripped, connecting this clutch member with the continuously operating clutch member 22. Through this mechanism, the knotter shaft 19 is driven by the chain 25, and the crank 27 is swung upwardly elevating the crank 31 until the gravity pawl 34 drops by its own weight and engages the second crank 33. Then upon the downward stroke of the crank 27, through the pitman connection 29 and crank 31, the pawl 34 is swung clockwise swinging the arm 35 with the roller 36 upwardly and rearwardly. This upward and rearward movement of the crank 35 is transmitted to the shock receptacle 16, setting the shock in a vertical position and swinging the butt teeth 43 and 44 into the position shown in dotted lines in Figs. 1 and 2. As the tines 44 are swung downwardly from their normal vertical position to their dotted line position shown in Figs. 1 and 2, they are swung outwardly into diverging positions which, of course, throws the butts laterally or transversely with respect to the longitudinal or travel direction of the machine. It will, of course, be understood that as the shock is held prostrate in the shock receptacle 16, the tines 43 and 44 penetrate the butts or, in other words, ex-

tend in a vertical plane through the butts of the shock as shown in Fig. 2 and that as the shock is being set, the tines 47 are swung laterally outwardly on their pivot pins 46, 5 thereby swinging the butts of the sheaves engaged by these tines, outwardly. Then as the shocker machine is withdrawn from the shock thus set, with the tines in the position shown in dotted lines in Fig. 1, the forward bundles of the shock will be engaged by the more divergent or separated portions of the tines 44 and as these tines are withdrawn forwardly, the forward or front bundles are further spread. It will also be noted 10 that as these tines are withdrawn, they offer a resistance or have a dragging action on the bundles thus engaged by these tines and has a tendency to pull the butts of these bundles forwardly spreading the shock in a longitudinal direction as well as in a transverse direction.

While in the above specification I have described one embodiment which my invention may assume in practice, it will of course be 25 understood that the same is capable of modification and that modification may be made without departing from the spirit and scope of my invention as expressed in the following claims.

30 What I claim is:

1. In a shocking machine, the combination of a shock discharging mechanism, means engaging the shock when the same is discharged, and means for positively and 25 automatically moving said means to increase the size of the shock butt as the shock is being set by the discharging mechanism.

2. In a shocking machine, the combination of a shock discharging mechanism, 40 means engaging the butt of the shock when the same is discharged, and means for positively and automatically operating said means to increase the size of the butt of the shock as the shock is being set by the discharging mechanism.

3. In a shocking machine, the combination of a shock discharging mechanism, means engaging the shock during the discharge thereof, and means for automatically operating said means as the shock is in transit to increase the size of the shock butt in all directions in a horizontal plane.

4. In a shocking machine, the combination of a shock discharging mechanism, 55 means engaging the shock during the discharge thereof, and means for automatically operating said means during the discharging operation to spread the shock laterally.

5. In a shocking machine, the combination of a shock discharging mechanism, tines for engaging the shock, and mechanism for automatically moving the tines laterally during discharge to spread the shock.

6. In a shocking machine, the combination of a shock discharging mechanism,

means for engaging the shock during the discharge thereof to increase its size in a longitudinal direction, other means for engaging the shock during the discharge thereof to increase its size in a lateral direction, 70 and means for positively and automatically moving said latter means laterally as the shock is being discharged.

7. In a shocking machine, the combination of a shock discharging mechanism, stationary means for engaging the shock during the discharge thereof to increase its size in a longitudinal direction, and automatically movable means for engaging the shock during the discharge thereof to increase its size in a lateral direction.

8. In a shocking machine, the combination of a shock discharging mechanism, means positioned on the opposite sides of the machine engaging the butts of the sheaves forming the shock during the discharge thereof, and mechanism for automatically moving said means to spread the butts of the sheaves laterally as the shock is set.

9. In a shocking machine, the combination of a shock discharging mechanism, movable means for spreading the shock as the same is set, and means positively controlled and actuated by the setting of the shock for moving the spreading means.

10. In a shocking machine, the combination of a shock discharging mechanism, movable means engaging the butts of sheaves in the shock as the same is set, and means positively controlled and actuated by the setting of the shock for moving said means to increase the size of the butt of the shock.

11. In a shocking machine, the combination of a shock discharging mechanism, 105 means for increasing the size of the shock in one direction controlled by the withdrawal of the shocker from the shock set thereby, and other means positively controlled and actuated by the setting of the shock for moving the latter means to increase the size of the shock in another direction.

12. In a shocking machine, the combination of a shock discharging mechanism, and 115 means pivotally mounted on the machine and actuated and controlled by the withdrawal of the shocker from the shock set thereby for positively moving said means to increase the size of the shock.

13. In a shocking machine, the combination of a shock discharging mechanism, and oppositely disposed means pivotally mounted on the machine and actuated and controlled by the withdrawal of the shocker from the shock set thereby for positively moving said means to increase the size of the shock.

14. In a shocking machine, the combination of a shock discharging mechanism, and 130

single unitary means for automatically increasing the size of the shock in longitudinal and transverse directions as the same is being set.

15. In a shocking machine, the combination of a shock discharging mechanism, a butt spreading mechanism mounted on said discharging mechanism, and means carried by said machine for automatically actuating said butt spreading mechanism as the shock is set.

16. In a shocking machine, the combination of a shock discharging mechanism, butt spreading mechanism pivotally mounted on said discharging mechanism for longitudinal and transverse movement, and means carried by said machine for automatically actuating said spread mechanism in both directions as the shock is being set.

17. In a shocking machine, a shock discharging mechanism, butt spreading mechanism pivotally mounted on said discharging mechanism for longitudinal and transverse movement, and cams carried by said machine for actuating said spreading mechanism in both directions.

18. In a shocking machine, the combination of a shock discharging mechanism, a plurality of pivoted tines carried by said mechanism and normally held in substantially a vertical position, and means for automatically actuating said tines to spread said tines with respect to each other when a shock is being set.

19. In a shocking machine, the combination of a shock discharging mechanism, a plurality of pivoted tines carried by said mechanism and normally held in substantially a vertical position, and means actuated by the movement of said discharge mechanism to spread said tines with respect to each other.

20. In a shocking machine, the combina-

tion of a shock discharging mechanism, a plurality of sets of tines pivoted to said mechanism, and means for actuating said tines by the movement of said discharge mechanism.

21. In a shocking machine, the combination of a shock discharging mechanism, a plurality of tines pivoted to said discharging mechanism, and means for moving said tines laterally and rearwardly with respect to said mechanism for automatically spreading the shock set by said discharging mechanism.

22. In a shocking machine, a shock discharging mechanism, a plurality of tines pivoted to said discharging mechanism in a normally vertical position in parallel relationship with respect to each other, and means for actuating said tines to assume a rearwardly diverging position as the shock is set by said discharging mechanism.

23. In a shocking machine, a shock discharging mechanism, a shaft provided with a plurality of tines pivoted to said discharging mechanism, a latch carried by said discharging mechanism, a pawl mounted on said shaft engageable with said latch for locking said pawl and normally holding said tines in a vertical position, and means carried by said pawl for automatically unlocking said latch when said discharging mechanism assumes a predetermined position.

24. In a shocking machine, a butt spreading mechanism carried thereby, a latch mounted on said discharging mechanism, and means carried by said butt spreading mechanism engageable with the latch for locking said butt spreading mechanism in a predetermined position and for automatically unlocking said latch.

In testimony whereof I affix my signature.
CLEMMA R. RANEY.

CERTIFICATE OF CORRECTION.

Patent No. 1,659,002.

Granted February 14, 1928, to

CLEMMA R. RANEY.

It is hereby certified that error appears in the printed specification of the above numbered patent requiring correction as follows: Page 4, line 1, claim 14, strike out the word "single", and line 18, claim 16, for the word "spread" read "spreading"; and that the said Letters Patent should be read with these corrections therein that the same may conform to the record of the case in the Patent Office.

Signed and sealed this 20th day of March, A. D. 1928.

Seal.

M. J. Moore,
Acting Commissioner of Patents.
